COMBINATION GAS AND OIL BURNER

Filed June 15, 1926

UNITED STATES PATENT OFFICE

ALBERT W. MORSE, OF LONG ISLAND CITY, NEW YORK

COMBINATION GAS AND OIL BURNER

Application filed June 15, 1926. Serial No. 116,143.

This invention relates to improvements in fuel burners and more particularly to burners of the kind which are adapted to use either liquid fuel or gas and more especially to burners of the externally mixing, low pressure air type, viz burners in which the fuel and the air do not meet until they are ejected from the burner.

A burner of this kind is illustrated in the Patent #1,406,238, issued to Stevenson and Bathgate, on February 14, 1922, and it is one of the objects of the invention to provide a burner of this type with an improved gas nozzle which discharges the gas into the air issuing from the burner in such a way as to cause a better mixture than heretofore; another object is to provide a wider as well as freer burning flame; a further object is to use lower air pressure and obtain an even greater intensity of flame than that obtained with former constructions using considerably higher air pressures; a still further object is to enable the gas burner to be operated on natural draft only with excellent result, where a lower temperature flame is desired. Other objects of the invention will appear in the following specification in which a preferred form of the fuel burner is described.

The invention is illustrated by the aid of the accompanying drawings in which—

Fig. 1 is a vertical longitudinal sectional view of the burner;

Fig. 2 is a transverse cross sectional view taken along the plane of line 2—2 in Fig. 1;

Fig. 3 is an enlarged fragmentary longitudinal sectional view of the gas nozzle of the burner and its adjacent parts;

Fig. 4 is a plan view of the nozzle; and

Fig. 5 is a view similar to Fig. 3, showing a modified construction of the nozzle.

Like characters of reference denote similar parts throughout the several views and the following specification.

10 is a cylindrical casing of substantially L shape; its shorter branch 11 is threaded interiorly to receive an air supply pipe 12. The terminal of the longer branch 13 of casing 10 is threaded exteriorly at 14. A tubular chamber 15 formed by wall 16 extends through the casing 10 in axial alignment with

its longer branch. Wall 16 connects the chamber 15 with the outer wall of the casing 10 opposite its shorter branch 11 and is threaded interiorly for connection with a gas supply pipe 17.

Casing 10 is bored out, adjacent to branch 11, to receive an "oil spindle" 18. This oil spindle is of hollow construction, being provided with a central duct 19, and extends through the tubular chamber 15 in central alignment therewith. 20 is an enlarged outer end of spindle 18 threaded internally to receive a spray plug 21 of the usual design employed with the low pressure, externally atomizing, oil burner. 22 is a nozzle cap screwed onto the exterior of the wall 16 and contacts with the spray plug 21, thereby forming a closure for the tubular chamber 15. Cap 22 is provided with a central opening 23 and deflecting faces 24. 26 are a number of drilled openings through cap 22. These openings are drilled radially i. e. their axes converge to a common center within the burner and are, in other words, diverging outwardly from the axis of the burner outlet, and they are further, preferably, arranged in two or more circular rows and in staggered relation to each other. 27 is a cap adapted to screw onto the threaded end 14 of branch 13 of casing 10, which cap is provided with a central and circular opening 28 and with lugs 28^a to facilitate screwing the same onto the threaded part 14.

29 is a reduced portion of oil burner spindle 18, projecting outside of the casing 10, and is threaded exteriorly to receive a needle valve 30 of standard construction, a spindle 31 of which controls a port 32 through which oil is admitted into duct 19 of spindle 18, supplied through a pipe 33.

In Fig. 5 is shown a nozzle cap 22^a essentially of the same construction as cap 22, having a central opening 23, deflecting faces 24, and radially disposed outlets 26. In addition thereto I have provided this cap with an annular projecting flange 25 around the extreme outer edge of faces 24 for the purpose specified hereafter.

The operation of the device is as follows: Oil is admitted, as is usual with oil burners

of this class, through supply pipe 33 and needle valve 30, whence it passes through duct 19 and through burner nozzle or spray plug 21 out at the front end of the burner, where it mixes with air under low pressure, forced into the casing 10 through pipe 12, which pipe is of relatively large diameter necessary to supply sufficient oxygen for perfect combustion. This air is 10 deflected by means of cap 22 and more particularly faces 24 coating with inner wall 27^a of cap 27 towards the spray of oil issuing from spray plug 21.

Should it be desired to change the fuel from 15 oil to gas, the oil control valve 30 is closed and the gas supply valve (not shown) is opened. Gas then passes through the pipe 17 into the chamber 15 whence it issues through the openings 26 of cap 22, out at the front end of the 20 burner. By means of the radially disposed outlets 26 of the nozzle cap 22, the gas is discharged into the air from the burner away from the center of the flame, which careful experiments have shown to result in a better 25 mixture and a larger and freer burning flame. Owing to more rapid combustion I obtain a higher intensity of flame than heretofore. By the use of the modified construction shown in Fig. 5, the gas at its outlet is protected from 30 the velocity of the air and the resistance to the flow of gas is thus reduced, permitting the use of lower gas pressures, or higher air pressures. Owing to the wide dispersion of the gas away from its center, the gas burner may 35 be operated on even natural draft only, where a flame of relatively low temperature is satisfactory, because little pressure is needed to thoroughly mix with the gas jets divergently discharged from the nozzle outlets 26. Particularly 40 good results are obtained by increasing the number of circularly disposed outlets and decreasing the size of each outlet for the obvious reason that in this manner the gas is broken up and its jets directed into the air 45 from the burner in fine streams to be still further broken up individually very easily.

It is obvious that the oil and gas features of this burner are entirely independent of each other, and that the fuel can be instantly 50 changed from oil to gas should such exigency occur.

Should it be desirable to discharge an extraordinarily large volume of gas, it will be noticed that by slightly unscrewing the central cap 22, opening 23 will serve as an auxiliary gas passage for that purpose. Moreover, the central opening 23 in the cap 22 may be omitted entirely and the burner operated as a gas burner only, and if desired, the structure 55 of the casing of the burner varied accordingly. Furthermore, while I have shown and described the outlet ports to be radially disposed, I do not wish to limit myself to this particular arrangement, but any disposition 60 of ports which causes jets of gas to be dis-

charged divergently at the outlet end of the burner may be used.

It is understood that while I have shown above the invention as applied to one kind of burner, its use and application may be varied 70 and serve other kinds of burners as well, such as are used with powdered coal for instance.

Various other changes in the form, proportion and minor details of construction may be resorted to without departing from the 75 principle or sacrificing any of the advantages of the invention as defined in the appended claims.

What I claim as new, is:

1. In a fuel burner, a liquid fuel supply 80 pipe extending through the burner, a gas chamber surrounding the said liquid fuel supply pipe, a spray nozzle at the terminal of the fuel supply pipe, a cap contacting with and enclosing the said spray nozzle and serving as a closure to the said gas chamber having a number of circularly disposed ports having their axes inclined to common centers, adapted to discharge diverging jets of gas at the outlet end of the burner, and means, independent of the said liquid fuel supply pipe, to admit gas to the said chamber.

2. In a fuel burner, a liquid fuel supply 85 pipe extending through the burner, a gas chamber surrounding the said liquid fuel supply pipe, a spray plug at the terminal of the liquid fuel supply pipe, an adjustable cap 90 serving as a closure to the said gas chamber and contacting with the said spray plug, the said adjustable cap being provided with a central opening and a number of circularly disposed other openings having their axes inclined to common centers, the latter adapted to discharge gas in diverging jets at the outlet 95 end of the burner, and means at the outlet end of the burner to deflect air against the 100 said jets of gas.

In testimony whereof I have hereunto set my hand.

ALBERT W. MORSE.
